UNITED STATES PATENT OFFICE.

WALTER A. SIMOND, OF FRANKLIN, NEW HAMPSHIRE, ASSIGNOR TO ACME KNITTING
MACHINE & NEEDLE COMPANY, OF FRANKLIN, NEW HAMPSHIRE, A CORPORATION
OF NEW HAMPSHIRE.

KNITTING MACHINE.

Application filed August 24, 1923. Serial No. 659,088.

To all whom it may concern:

Be it known that I, WALTER A. SIMOND, a citizen of the United States, residing at Franklin, in the county of Merrimack and State of New Hampshire, have invented certain new and useful Improvements in Knitting Machines, of which the following is a specification.

This invention relates to the knitting of seamless hosiery and is concerned more especially with the knitting of hosiery which includes both ribbed and plain work.

It has been proposed heretofore to knit hosiery with a plain foot and a ribbed leg, and it has also been proposed to further vary the knitting of the leg by changing the style of the ribbed knitting near the top, using, for instance, a four and one rib for the greater part of the leg and a two and one rib at the top. Usually, however, it has been customary to maintain a uniform number of stitches throughout the leg and top, and frequently, also, this same number is maintained throughout the foot, the shaping of the leg being produced by decreasing the length of the stitch as the knitting operation proceeds from the top of the stocking toward the toe. This process, and all the prior processes of which I am aware, of knitting hosiery of the character above described require the transfer of stitches from one set of needles to the other when the change is made from ribbed knitting to plain knitting, and the knitting machine must be run at a very low speed while this transfer is effected. In cases where it has been proposed to use a finer rib at the top of the stocking than through the main portion of the leg, it has been necessary to make another transfer of stitches between the two ribbed sections, and this second transfer also necessitates the slowing down of the machine. Furthermore, when these transfers are made automatically, there is always the danger of producing imperfect work.

The present invention aims to improve machines for knitting hosiery of the type including both ribbed and plain work with a view to simplifying the knitting operations, reducing the liability of producing flaws or imperfect work, increasing the rate of production, and avoiding the necessity of transferring stitches.

The nature of the invention will be readily understood from the following description when read in connection with the accompanying drawings, and the novel features will be particularly pointed out in the appended claims.

In the drawings,

Fig. 1 is a plan view of the adjusting and controlling mechanism for the dial needles of a knitting machine embodying this invention;

Fig. 2 is a plan view of a section of the pattern wheel by means of which the dial needles are adjusted;

Fig. 3 is an enlarged plan view of a part of the dial cam adjusting mechanism;

Fig. 4 is a plan view, partly in cross section, of the dial needles and the dial cams showing these parts in their relationship to the cylinder needles;

Fig. 5 is a cross sectional view through a part of the dial cam mechanism;

Figs. 6, 7 and 8 are plan views of different dial cam segments; and

Fig. 9 is a view illustrating the difference in the heights of butts of the dial needles.

The invention will be herein described in connection with a machine constructed and organized substantially in accordance with the disclosure in pending application Serial No. 546,563 filed March 25, 1922, assigned to the assignee of the present invention. The detailed description in the present application will be confined more especially to those features in which this invention departs from the disclosure made in said application, and reference should be made to the earlier application for a detailed description of the construction and operation of the machine as a whole.

For the purposes of the present application it is sufficient to state, with regard to this earlier machine, that it includes a cylinder and a dial carrying independent sets of needles, suitable cams for operating the needles, and automatic controlling mechanism for causing the machine to knit either a plain or ribbed fabric, and to change automatically from one of said styles of knitting to the other. So far as the cylinder needles and their operating mechanism is concerned, the present invention makes no change whatever in the machine shown in the appli-

cation above designated. The dial of the machine shown in the accompanying drawings, however, includes three sets of needles. Referring more particularly to Fig. 4, the 5 dial is indicated at 2, the cylinder needles at 3, and the dial needles at 4, 5 and 6, respectively. The alternate needles in the dial have short butts and are designated by the numeral 4. The remaining needles have 10 longer butts and these long butt needles are divided into two groups, those in the lower half of the dial shown in Fig. 4 and designated by the numeral 5 having longer butts than those located in the upper half of the 15 dial and designated by the numeral 6.

The dial cams for operating these needles include a rear adjustable cam 7 and a front cam consisting of three cam segments 8, 9 and 10, respectively. All of these cams are 20 mounted to be swung inwardly into inoperative positions or outwardly into operative positions, and the three cam segments are superposed one upon the other and all mounted to swing about a common pivotal 25 axis. The cams just mentioned simply act to project the needles, and for the purpose of withdrawing or retracting them additional outer cam members are provided including a stitch cam 12 having a stitch drawing point 14. Other of the outer cam members are indicated at 15, 16 and 17, respectively, Fig. 4.

For the purpose of adjusting the front cam segments into and out of their operative 30 positions, the segments 9 and 10 are pivoted on the pivot stud 20 of the lowermost segment 8. These two segments 9 and 10 have studs 21 and 22 fixed therein and extending upwardly through slots formed in the dial 35 cam cap 24, Figs. 1 and 3. An arm 25, Figs. 1 and 3, is secured to the stud 20 above the dial cam cap, and this arm is connected by a link 26 to a lever 27 which is pivoted on a shaft 28 mounted on the rotating cam plate 40 45 29 near one side thereof. A coiled spring 30 acts on this lever in a direction tending to swing the cam 8 inwardly into its inoperative position.

For the purpose of locking the cam 8 out 50 in its operative position, the lever 27 has a lock or bracket 32, best shown in Fig. 3, fastened thereto and provided with a notch 33 adapted to be engaged by the end of a latch 34, this latch being drawn toward the lock 55 32 by a spring 35. The outer ends of the latch 34 and lock 32 are located at different elevations and are arranged to strike, at certain times, the edge of a disk or controller 60 65 36 mounted on the upper end of a vertical rod 37 which is raised and lowered by cam lugs, such as those indicated at 38, Fig. 2, mounted in a pattern wheel 40. The mechanism for adjusting the controlling disk 36 is exactly like that shown and described in 65 the pending application above designated.

The cam segment 9 is adjusted in the same manner, its stud 21 being connected by a link 42, Fig. 1, to a lever 43 fulcrumed on a shaft 44 and acted upon by a spring 45 which tends to hold the cam segment in its innermost position. A lock 46 is secured to the lever and cooperates with a latch 47, all these parts being substantially like those provided to move the cam segment 8. This latch and lock are operated by a disk 48 like the disk 36, and arranged to be moved into different elevations by lugs on the pattern wheel 40 in the manner fully described in the application above referred to.

The stud 22 of the cam segment 10 is connected by a link 50 to an arm 51 secured fast on the shaft 44, and a coiled spring (not shown) encircles this shaft and acts on it in a direction tending to move the cam segment 10 to its innermost position. Another arm 51', also secured on the shaft 44, has a point or toe 52 arranged to be engaged by a spring pressed latch 53 to lock the cam segment 10 in its outermost or operative position. The outer ends of the latch 53 and arm 51' are arranged to be engaged by the disk 48 at certain times to release the latch or to move the arm into position to be engaged by the latch.

The rear cam 7 is adjusted in much the same manner as the cams above described, but has two operative positions. This cam has a stud or pin 55 extending through the dial cam cap, and it is connected by a link 56 to an arm 57 which is secured to the shaft 28, previously referred to. A lock 58 is also secured on this shaft and has a toe or point arranged to be engaged by either of two latches 59 and 60. One of these latches holds the cam 7 in an intermediate position, while the other holds it in its outermost position. Springs coiled about the pivots of these latches act on them to hold them normally in latching position, and their outer ends are arranged to be engaged by the disk 36 at the desired times. The lock 58 is provided with two wings or lugs at its outer end, designated at 62 and 63, respectively, which are located at different elevations so that they may be selectively engaged by the disk 36 to move the cam 7 into either its intermediate or outermost position after it has been adjusted in its innermost position.

It will now be evident that by the employment of suitable lugs in the pattern wheel 40 the three groups of needles can be selectively brought into or put out of operation. It should also be noted that the cams are locked in their outermost or operative positions and are held yieldingly in their inoperative positions. This arrangement has the advantage of preventing the cams from being moved accidentally out of operative position by a bent or broken needle. The cam arrangement above de-

scribed also avoids the use of cam parts which are grooved to receive the butts of the needles and which, consequently, are difficult to make.

5 Preferably the knitting operation on the stocking is, contrary to the usual practice, commenced at the toe and proceeds upwardly. Assuming, for example, that a stocking is to be knit having a plain foot, a ribbed 10 instep and a ribbed leg with a finer rib at the top of the leg, the machine would be started in operation in the usual manner, the knitting operation at first being performed simply by the cylinder needles to 15 form a plain toe. After knitting a few courses the machine would fashion the toe pocket by reciprocating knitting in the well known manner, and a few circular courses would then be made on the cylinder needles 20 in order to facilitate the looping operation after the stocking is completed. The cam 10 is next swung into its operative position through a proper adjustment of the disk 36 by the pattern mechanism. This cam throws 25 the long butt needles 5 in one-half of the dial cylinder into action. These needles immediately take thread and cooperate with the needles in one half of the cylinder to knit a four and one ribbed instep while the 30 other cylinder needles knit a plain fabric bottom in the foot. This action continues until the heel is reached, when the knitting operation is stopped on half of the cylinder needles and all the dial needles in operation 35 at this time, while the pocket is formed by reciprocating knitting in the usual manner. Upon the resumption of circular knitting, a plain fabric will be formed in the back of the ankle and a four and one ribbed 40 fabric at the front of the ankle. At the desired point in the ankle or leg the cam 9 will be swung into its operative position, thus bringing into action the dial needles 45 in the opposite side of the dial to that occupied by the needles 5. These needles will immediately form stitches and the entire set of needles then in action will produce a four and one ribbed fabric. This operation will be continued until a leg of the 50 desired length has been formed and the point is reached where it is desired to begin the knitting of a finer ribbed top. At this point the pattern mechanism will move the lowermost cam segment 8 into its operative 55 position, thus throwing into action the needles 4 which, up to this time, have been idle. All of the dial needles and all of the cylinder needles will then knit, with the result that a two and one ribbed fabric will 60 be formed at the top of the stocking. When the desired length of top has been completed, the dial needles will be withdrawn, suitable welts and a few loose courses usually being formed at this point to facilitate 65 the separation of the stocking from that

next formed, and the operations above described will then be repeated.

By beginning the knitting operation at the toe of the stocking and knitting upwardly, and introducing additional needles to 70 change the character of the knitting operation, it is unnecessary to transfer stitches or to greatly reduce the speed of the knitting operation when such changes are made. This not only enables the process above 75 described to be carried out with a simpler mechanism than otherwise would be possible, but it makes it possible to increase the rate of production, and it greatly reduces the danger of breaking threads, mis-stitching, or producing other flaws or imperfections in the work during the periods of transition from one style of knitting to another. During such periods the knitting operation may not only be continued uninterrupted, but continued without any great reduction in speed.

A more comfortable and better fitting stocking is produced by this process. In the knitting of this stocking, additional 90 needles are brought into action in producing successive portions of the stocking of increased diameter, so that the number of stitches is increased at points of increased 95 diameter. At the same time, the length of the stitch can be adjusted so as to obtain all the advantage of fashioning by this expedient that has been possible heretofore. The increase in the number of stitches and in the width and elasticity of the top of the 100 stocking which is obtained by this process is of particular value in producing a better fitting and more comfortable stocking.

When additional needles are introduced to change from one style of knitting to another, as above described, it is preferable to throw the rear cam 7 to an intermediate position for the first two courses after the change is made so that the dial needles will first make tuck stitches and thus reduce the 110 size of the "eyelets" or openings in the fabric formed by making this change.

While I have herein shown and described the best embodiment of my invention that I have so far devised, it will be understood 115 that the invention may be embodied in other forms without departing from the spirit or scope thereof.

Having thus described my invention, what I desire to claim as new is:

1. In a circular hosiery knitting machine, the combination of a cylinder, a series of cylinder needles supported therein, a dial, a circular series of dial needles mounted in said dial in cooperative relationship to said cylinder needles, the alternate needles in said dial having long butts and the remaining needles having short butts, the long butt needles in one-half of the dial having 125 longer butts than those in the other half of 130

said dial, and operating instrumentalities for all of said needles including means for operating said dial needles having butts of certain lengths to the exclusion of dial needles having butts of a different length.

2. In a circular hosiery knitting machine, the combination of a cylinder, a series of cylinder needles supported therein, a dial, a circular series of dial needles mounted in said dial in cooperative relationship to said cylinder needles, the alternate needles in said dial having long butts and the remaining needles having short butts, the long butt needles in one-half of the dial having longer butts than those in the other half of said dial, operating instrumentalities for all of said needles including three superposed dial cam segments for selectively operating said dial needles, and means for automatically adjusting said cam segments independently

of each other to operate the desired set of said dial needles.

3. In a circular hosiery knitting machine, the combination of a cylinder, a circular series of cylinder needles supported therein, a dial, a circular series of dial needles mounted in said dial in cooperative relationship to said cylinder needles, the alternate needles in said dial having long butts and the remaining needles having short butts, the long butt needles in one-half of the dial having longer butts than those in the other half of the dial, operating instrumentalities for all of said needles including adjustable cam means for giving said dial needles their knitting movement, and automatic mechanism for adjusting said means to operate certain of said dial needles to the exclusion of others.

WALTER A. SIMOND.
